CLAIM

The ornamental design for a decorative lid of a holder for foodstuff trays, tins, and pans, as shown and described.

DESCRIPTION

FIG. 1 is a perspective view of a lid of a decorative holder for foodstuff trays, tins, and pans according to our new and ornamental design, shown in a condition of use;

FIG. 2 is another perspective view thereof;

FIG. 3 is a rear view thereof;

FIG. 4 is a bottom perspective view of a lid of a decorative holder for foodstuff trays, tins, and pans according to our new and ornamental design;

FIG. 5 is a perspective view thereof;

FIG. 6 is a rear view thereof;

FIG. 7 is a right side view thereof;

FIG. 8 is a left side view thereof; and,

FIG. 9 is a top view thereof.

The broken lines illustrate portions of the decorative holder for foodstuff trays, tins, and pans that form no part of the claim. The broken lines in FIGS. 1-3 show the lid attached to a base and a cover of a decorative holder and illustrate the environment in which the lid is used.
